UNITED STATES PATENT OFFICE

96,560

DESIGN FOR A MERCHANTISING CABINET

Walter W. McNamara, Visalia, Calif.

Application January 21, 1935, Serial No. 54,985

Term of patent 14 years

To all whom it may concern:

Be it known that I, Walter W. McNamara, a citizen of the United States of America, residing at Visalia, in the county of Tulare and State of California, have invented a new, original, and ornamental Design for a Merchandising Cabinet, of which the following is a specification, reference being had to the accompanying drawing, forming a part thereof.

I claim:

The ornamental design for a merchandising cabinet as shown.

WALTER W. McNAMARA.
